UNITED STATES PATENT OFFICE

TALLMAN LADD, OF CORAOPOLIS, PENNSYLVANIA, ASSIGNOR TO INTERNATIONAL COMBUSTION ENGINEERING CORPORATION, OF NEW YORK, N. Y., A CORPORATION OF DELAWARE

FURNACE WATER WALL OR BAFFLE

Application filed August 17, 1928. Serial No. 300,269.

This invention relates to furnace water walls or baffles and is particularly adapted for use in connection with walls or baffles which are composed of finned water tubes.

5 Among the more important objects of the invention are the provision of means in the nature of a channel-like member for joining or sealing adjacent tube fins in the wall and the provision of means for protecting the fin joining means from excessive heat.

10 How the foregoing together with such other objects and advantages as may appear hereinafter are obtained will be clear from a consideration of the following description taken 15 with the accompanying drawings which illustrate the preferred embodiment of the invention and in which

Figure 1 is a fragmentary side elevation of a group of tubes with the device of the present invention applied thereto.

20 Figure 2 is a horizontal sectional view taken as indicated by the line 2—2 of Figure 1.

25 Figure 3 is a vertical sectional view taken as indicated by the line 3—3 of Figure 1.

Figure 4 shows a modification of the manner in which the device may be secured to the fins of the tubes, and

30 Figure 5 discloses a modified form of a detail of the invention.

Referring now particularly to Figures 1, 2 and 3 the water tubes are indicated by the reference letter 6 and the fins which extend longitudinally on adjacent sides of the tubes are indicated at 7, the same being spaced apart a small distance.

35 In all ordinary construction it is practically impossible to arrange the tubes accurately and closely enough to make their fins abut and provide a substantially unbroken wall; hence small spaces always occur between the fins.

40 Between the tubes 6 and overlying adjacent pairs of fins 7 I have provided channel-like members 8 positioned with their sides or legs 9 adjacent to the fins. These channel-like members 8 are secured and carried on the fins 7 by means of wedging mechanisms, each one of which includes an apertured lug 10 secured to a fin 7 in some suitable manner as by welding and extending

outwardly therefrom thru a recess 11 formed in a side of a member 8. Wedges 12 are inserted in the apertures in the lugs 10 and engage the channel-like members 8 to support and secure the same in position.

55 Between the channel-like members 8 and the fins 7 I interpose some suitable heat insulating and packing material 13 such, for example, as asbestos.

It should be noted that the use of a member which is channel-like in form results in a construction which is not only very rigid and strong, but which is also advantageous as the legs 9 of the channels 8 cooperate with the fins 7 to form a pocket which is conveniently adapted to receive the insulating and sealing material 13.

60 When the device is used in connection with finned tubes which compose or occupy the position of a baffle, it is obvious that the sealing 76 of the space or openings between the fins renders the baffle very effective in diverting or directing gases thru the boiler.

When the device is used in conjunction with a finned tube lined combustion chamber, the 75 channel-like members 8 are, of course, positioned on the side of the fins 7 away from the combustion chamber and in this case the insulating material 13 effectively protects the members 8 and their wedge supporting means 80 from radiant heat. It might be noted that the device is particularly useful in connection with the walls of a furnace combustion chamber which is adapted to burn pulverized fuel admitted tangentially or in some other swirling or violently eddying manner. In such cases the fuel and ash particles swirl and move around in the combustion chamber in such manner that they very readily work their way thru and frequently clog and build up 85 around the spaces or cracks between the fins.

The sealing means of this invention effectively prevents the passage of fuel and ash particles between the fins and presents a substantially unbroken surface to the combustion 90 chamber so that such particles do not adhere to and build up on the edges of the fins.

95 In places where the tubes to which the device of this invention is to be applied, extend substantially horizontally the wedges 12 100

might have a tendency to work loose. In order to completely obviate this difficulty the small ends of the wedges may be bent to one side after they have been inserted through
5 the apertures in the lugs 10. This is illustrated in Figure 4. The wedge illustrated in Figure 5 having a longitudinal slit at its narrow end forming the prongs 14 may also be used in places where the tubes to which
10 the device is applied extend substantially horizontally. The prongs 14 of this wedge may be bent in opposite direction in order to effectively prevent the wedges from loosening and working out of the apertures in the lugs
15 10.

I claim:—

1. A water wall construction including a row of tubes, fins on adjacent sides of the tubes and channel-like members for joining
20 adjacent fins, the legs of the said members being positioned adjacent to the fins, together with insulating material in said channel-like members.
2. A water wall construction including a row of tubes, fins on adjacent sides of the tubes, channel-like members for joining adjacent fins, the legs of the said members being positioned adjacent to the fins and insulating material in the channel-like members, together with means for securing said members to the fins including apertured lugs secured to the latter and extending therefrom through openings in the members and wedges cooperating with the lugs and engaging the members.
30
3. A water wall construction including a row of tubes, fins disposed on adjacent sides of the tubes and spaced apart and means for sealing the spaces including members extending along and secured to the fins and insulating material between the members and the fins.
40

In testimony whereof I have hereunto signed my name.

45 TALLMAN LADD.
